CLAIM

The ornamental design for a clock, as shown and described.

DESCRIPTION

FIG. 1 is a front elevational view of my novel clock design having a basic octagonal shape with a geometric design in combination with a feather design therebelow, showing the herringbone pattern and showing parallel stitching, as indicated by the parallel lines, in the feather design as well as at the edges of the octagonal shape;

FIG. 2 is a side view showing the parallel stitching;

FIG. 3 is a bottom view showing the parallel stitching; and, FIG. 4 is a rear view showing an opening for insertion of a battery.
